UNITED STATES PATENT OFFICE

91,986

DESIGN FOR A TANK

Walter L. Clark, Cambridge, Mass., assignor to
Riverside Boiler Works, Inc., Cambridge, Mass.,
a corporation of Massachusetts

Application December 8, 1933, Serial No. 49,991

Term of patent 7 years

To all whom it may concern:

Be it known that I, WALTER L. CLARK, a citizen of the United States, residing at Cambridge, county of Middlesex, and State of Massachusetts, have invented a new, original, and ornamental Design for a Tank, of which the following is a specification, reference being had to the accompanying drawing, forming part thereof.

Figure 1 is an elevational view of the head or top of the tank;

Figure 2 shows on a reduced scale the complete tank equipped with the head shown in Figure 1; and

Fig. 3 is a plan view of the tank head.

The dominant feature of the design is the head of the tank.

I claim:

The ornamental design for a tank, as shown and described.

WALTER L. CLARK.
